UNITED STATES PATENT OFFICE.

WILLIAM E. GIBBS, OF EAST ORANGE, NEW JERSEY, ASSIGNOR TO NEW JERSEY PATENT COMPANY, OF WEST ORANGE, NEW JERSEY, A CORPORATION OF NEW JERSEY.

PHONOGRAPH.

Application filed May 1, 1920. Serial No. 378,182.

To all whom it may concern:

Be it known that I, WILLIAM E. GIBBS, a citizen of the United States, and a resident of East Orange, in the county of Essex and State of New Jersey, have made certain new and useful Improvements in Phonographs, of which the following is a description.

My invention relates to phonographs, and 10 more particularly though not exclusively to disc phonographs of the Edison type.

The principal object of my invention is to provide an improved governor for a motor-driven device or mechanism such as a 15 phonograph, whereby it is insured that such device will be driven at the constant and uniform speed desired throughout the operation of the motor regardless of variations in the power or torque exerted by 20 such motor in driving said device, and the construction of which is such that the action thereof in maintaining the speed at which said device is driven, is preferably not dependent on fluctuations or variations 25 in such speed, as is usually the case in such governors, especially those of the centrifugal type.

My invention also contemplates a governor of this character which is extremely 30 efficient and simple in construction, which is unlikely to get out of order or function improperly and which is adapted when used for a phonograph, to be actuated directly by the comparatively slow rotating shaft on 35 which the record support or turntable is mounted.

Another object of my invention resides 40 in the provision in a phonograph, especially a disc phonograph of the Edison type, of improved means for automatically effecting the stopping of the phonograph at a predetermined point in the operation thereof and preferably comprising a brake coacting with a part of the governor; the 45 construction and arrangement preferably being such that the turntable or record support may be removed from the phonograph without releasing such braking means.

A further object of my invention resides 50 in an improved construction and arrangement of a phonograph mechanism within a cabinet whereby the parts of such mechanism are rendered readily accessible for cleaning, adjustment or other purposes.

55 Other objects and features of my in-

vention will be hereinafter more specifically described and claimed.

In order that my invention may be more clearly understood, attention is directed to the drawings accompanying and forming a 60 part of this specification and in which:

Figure 1 is a plan view, partly in section, of a phonograph having my invention applied thereto, the phonograph mechanism being shown in operation with the brake 65 mechanism held inoperative, the motor being omitted and the turntable being shown in dotted lines;

Fig. 2 is a view similar to Fig. 1 showing the phonograph held inoperative by 70 the brake mechanism which has been released by movement of the sound conveyer transversely of the record support to the position shown;

Fig. 3 is a fragmental sectional view taken 75 on line 3—3 of Fig. 1, parts being omitted;

Fig. 4 is a sectional view taken on line 4—4 of Fig. 2, parts being shown in elevation and parts being omitted;

Fig. 5 is an enlarged detailed sectional 80 view, partly in elevation, of the upper end portion of the turntable shaft and parts associated therewith; and

Fig. 6 is an enlarged view in side elevation of a detail of construction. 85

Referring to the drawings, reference character 1 represents the casing or cabinet of the phonograph and A a supporting frame which is mounted in the upper end portion of the cabinet. The frame A 90 comprises a rectangular top plate 3 provided on its under side and adjacent its rear edge with a pair of spaced apertured lugs 4, 4 through which a cylindrical rod 5 extends, this rod being suitably secured to 95 the top plate, as by means of set screws (not shown) threaded into the lugs 4, 4. The ends of the rod 5 are respectively pivotally mounted in horizontally aligned cylindrical sockets 6, 6 provided in brackets 100 7, 7 which are suitably secured, as by means of screws, to the opposite side walls of the cabinet 1. The top plate 3 is also provided on its under side adjacent its front edge, with a downwardly extending lug 8 105 which normally engages a horizontal rod 9 which extends across the cabinet 1 parallel to and substantially at the same height as the rod 5 and which is mounted at its ends in opposed brackets 10, 10 secured, as 110

2

by means of screws, to the opposite side walls of the cabinet 1. The sockets 6, 6 preferably open upwardly to permit the rod 5 to be lifted therefrom. It will thus be seen that the top plate 3 of the support A is normally maintained in a horizontal position in the cabinet 1 and that the support and parts carried thereby may be swung upwardly about the axis of the sockets 6, 6 and if desired may be lifted out of the cabinet, providing the sound conveyer and parts carried by the latter, which will hereinafter be described, are properly positioned.

15 The support A is provided with a pair of depending brackets in which any suitable motor, such as the spring motor 11, for driving the phonograph mechanism is mounted, only one of these brackets 12 being shown. Reference characters 13, 13 represent winding gears for the motor 11, and 14 a bracket depending from the support A and provided with a hub 15 having a cylindrical recess for the reception of the winding crank, (not shown). The motor 11 is provided with the usual worm wheel 16 which is in driving engagement with a worm 17 cut on the vertical turntable shaft 18. The turntable shaft 18 is supported at its lower end on a ball step bearing 19 carried by the lower end of a downwardly extending arm 20 of a bracket 21 comprising a part of the supporting frame A. The bracket 21 is secured, as by means of one or more screws 22, to the underside of a central circular depressed portion 23 of the top plate 3, and has a horizontal arm 24 engaging the lower surface of such portion 23 and provided with an upstanding cylindrical lug or boss 25 which extends into and fits closely a central opening 26 extending through the portion 23. The portion of arm 24 or bracket 21 provided with the lug 25, as an opening through which the turntable shaft 18 extends and in which it is journaled. The shaft 18 extends a considerable distance above the centrally depressed portion 23 of the top plate and has a cylindrical enlarged upper-end portion 27 which is provided with an axial tapered or conical recess 28 adapted to receive a tapered or conical pin 29 extending from and suitably secured to the under side of the rotatable record support or turntable 30 at the center thereof. Reference character 31 represents the reproducer which is connected to and supported for movement transversely of the record support or turntable 30 by the tapering sound conveyer or amplifier 32, the latter extending rearwardly from the reproducer, thence downwardly in the cabinet past the top plate 3 and thence forwardly toward the front of the cabinet beneath the supporting frame A and the motor 11 and other parts carried thereby. The large horizontally ex-

tending exit portion 33 of the sound conveyer or amplifier 32 terminates in the rear of the front of the cabinet 1 adjacent an opening 34 therein. The sound conveyer 32 is suitably secured adjacent its exit as by means of a pair of brackets 35 (only the upper one of which is shown) to a vertical rod 36 which is pivotally and slidably mounted in a pair of vertically aligned bearings 37 formed in suitable brackets 38 secured to the cabinet 1, only the upper bearing 37 and bracket 38 being shown. A horizontally extending arm 39 is pivotally mounted adjacent one end in a pair of spaced lugs 40 provided on the upper bracket 35, extends rearwardly from said lugs and is provided at its rear end with a segmental rack 41. The rack 41 is adapted to engage with and be driven by a worm 42 mounted on a horizontal shaft 43 adjacent one end thereof, the said shaft 43 being supported and journaled in a pair of spaced brackets 44 (only one of which is shown) depending from the top plate 3 and comprising a part of the supporting frame A. Secured to the shaft 43 adjacent its other end is a worm wheel 45 which engages and is driven from a worm 46 on a boss or sleeve provided on the turntable shaft 18 just above the worm 17. When the phonograph is in operation, the shaft 43 and thereby the worm 42 are rotated by reason of the driving engagement of the worm 46 and worm wheel 45, and the worm 42 coacting with the segmental rack 41 causes the sound conveyer or amplifier 32 to swing about the axis of rod 36 so as to impart to the reproducer 31 a feeding movement transversely of the record on the turntable 30. The rod 36 extends a slight distance above the upper bearing 37, and a member having a handle 47 is pivotally secured at 48 to the upper end portion of said rod. Below the pivot 48 this member is provided with a pair of similar spaced cams 49 engaging the upper surface of the upper bearing 37 whereby the latter serves to support the sound conveyer and the parts carried thereby. The construction is such that when the handle 47 is in a vertical position, as shown in Fig. 3, the sound conveyer or amplifier 32 will be supported from the bearing 37 in its lowermost and operating position with the reproducer 31 in operative relation to the record on the turntable 30 and with the segmental feeding rack 41 in engagement with its driving worm 42. Upon turning the handle 47 to the right from the position shown in Fig. 3, however, the cams 49 coact with the upper bearing 37 so as to effect upward movement of the rod 36 in the bearings 37 and thereby the raising of the sound conveyer 32 so as to move the reproducer 31 to inoperative position with respect to a record on the turntable 30. The arm 39 ex-

tends forwardly a slight distance from its pivotal mounting, and a vertical headed member 50 secured to the upper bracket 35 extends loosely through the forwardly extending portion of the arm and through a coil spring 51 disposed between the arm and the bracket 35. The spring 51 constantly tends to move the arm 39 to the right about its pivotal axis (referring to Fig. 3) and 5 maintain the rack 41 in engagement with the worm 42. The headed member 50, however, so limits this movement of the arm that the rack 41 will be disengaged from the worm 42 when the sound conveyer 32 is 10 raised by turning the handle 47 from the vertical position shown in Fig. 3 to a horizontal position. When the rack 41 is thus disengaged from the worm 42, the sound conveyer or amplifier 32 and the parts 15 carried thereby may be freely swung about the axis of the rod 36. If the conveyer 32 is then swung to the position shown in dotted lines in Fig. 1, the rack 41 will be so positioned as not to be engageable with the worm 42, and accordingly the support A and parts carried thereby may either be swung upwardly about the axis of rod 5 or be lifted entirely out of the cabinet 1 for inspection, 20 cleaning or repairing of the parts carried by the support A, or for any other purpose.

The central circular depressed portion 23 of the top plate 3 is provided with an upstanding annular rim 52 having an inner annular braking surface concentric with the 25 shaft 18, and comprising a part of my improved governor. The central portion 23 of the top plate and the lower portion of the rim 52 are provided with a large opening or cut-out O through which the upper portion of the motor 11 projects. The shaft 18 is provided just below its upper enlarged end portion 27 with a pair of collars or annular flanges 53 and 54, the upper collar 53 preferably being of greater diameter 30 than the lower collar 54. A horizontal circular disc 55 having an upstanding annular rim or flange 56 is rigidly secured to the lower collar 54 of the turntable shaft 18, such disc preferably being provided with a central circular opening in which the collar 54 has a tight fit; and a straight arm 57 35 loosely mounted midway between its ends on the enlarged upper end portion 27 of shaft 18, is supported on the upper collar or flange 53 by means of a ball-bearing 58. Two weights 59, 59 are respectively pivotally mounted at 60, 60 on the ends of arm 57 and extend from such arm in opposite directions within the casing formed by the annular rim 52 and the central portion 23 of the top plate 3. These weights are respectively provided with brake pads 61, 61 which extend therefrom at their outer edges, lugs 62, 62 at their inner ends adapted to cooperate with the arm 57 for limiting the movement of the weights inwardly, and lugs 63, 63 at their outer ends which are respectively connected by means of springs 64, 64 to lugs 65, 65 provided on the rim 56 of disc 55 at diametrically opposite points. A gear 66 in 40 the form of an annulus, is rotatably mounted on the collar 53 of shaft 18 and engages a small gear 67 fixed on the reduced end portion 68 of a vertical rod 69. Above the gear 67 the reduced portion 68 of rod 69 is rotatably mounted in a segmental plate 70; and a spring washer 71 disposed between the plate 70 and a shoulder 72 on the rod 69 normally frictionally holds the rod 69 and thereby the gear 67 against rotary movement 45 with respect to the plate 70. Below the gear 67 the reduced end portion 68 of rod 69, takes loosely into an opening provided in the disc 55. The segmental plate 70 is suitably secured to the disc 55 as by means 50 of screws 73 and is provided with a depending flange 74 at its periphery which serves to space the main portion of the plate 70 from the disc 55 a distance slightly in excess of the thickness of gear 67. It will thus 55 be seen that the gear 67 and thereby the gear 66 will normally be held against rotary movement with respect to the disc 55 and the shaft 18. The rod 69 is provided at its upper end with a slotted head 75 which when 60 the turntable 30 is mounted on the shaft 18 in proper position, is received in a circular opening 76 in the turntable. The gear 66 has suitably secured thereto at diametrically 65 opposite points on its upper surface, two members 77, 77 comprising vertical portions and horizontal arms 78, 78 which extend radially outward beyond the disc 55 at the upper ends of said vertical portions. The 70 arms 78, 78 are respectively connected at 75 their outer ends by springs 79, 79 to lugs 80, 80 which extend from the opposite edges of arm 57 adjacent its ends. A small plate 81 suitably secured to the upper end of the hub of arm 57, as by means of a screw 81', 85 extends inwardly of the hub into an annular groove 83' provided in the upper end portion of the enlargement 27 of shaft 18 and serves to prevent displacement of arm 57 and the 90 parts carried thereby longitudinally of the 85 shaft 18.

The operation of my improved governor is as follows: When the phonograph is in operation the motor 11 drives the shaft 18 and thereby effects rotation of the turntable 120 30, the disc 55 and gears 67 and 66 about the axis of said shaft. The arm 57 and the weights 59, 59 mounted thereon will then be dragged or rotated about the axis of shaft 18 by means of the springs 79, 79 connecting 125 the arm 57 with the members 77, 77 secured to the gear 66, and such weights will move outwardly about the pivots 60 under centrifugal action, against the tension of springs 64, 64 and bring the brake pads 61, 61 into 130

frictional engagement with the inner annular braking surface of the rim 52. The shaft 18, the disc 55 and the gear 66 will have an angular advance with respect to the 5 arm 57 dependent on the power or torque exerted by the motor at any time in rotating said shaft, and the springs 79, 79 will be extended or lengthened and the springs 64 contracted or shortened, that is, the effective 10 tension of springs 79, 79 will be increased and that of springs 64, 64 decreased. If the power or torque which the motor exerts in rotating shaft 18 now increases or is increased, the angular advance of shaft 18, 15 disc 55 and gear 66 and the tension of springs 79, 79 will be automatically further increased while the tension of springs 64, 64 will simultaneously be automatically further decreased. On the other hand, if the 20 power or torque exerted by the motor in driving shaft 18 decreases, the angular advance of shaft 18, disc 55 and gear 66 with respect to arm 57 and the effective tension of springs 79, 79 will automatically decrease 25 and the tension of springs 64, 64 will automatically increase. Where a spring motor is employed such as the motor 11 shown, the power or torque which the motor tends to exert to drive shaft 18 will be at a maximum 30 when the spring is fully wound. If the phonograph is then operated the shaft 18, disc 55 and gear 66 will assume a position of maximum angular advance with respect to arm 57 and the effective tension of springs 35 79, 79 will be at the maximum and that of springs 64, 64 at the minimum. Accordingly, the brake pads 61, 61 of weights 59, 59 will engage the annular braking surface of rim 52 with a maximum pressure by reason of 40 the action of centrifugal force on the weights. As the spring of the motor unwinds, that is, as the power or torque exerted by the motor in driving shaft 18 decreases, the angular advance of the shaft 18, disc 55 45 and gear 66 and the tension of springs 79, 79 will decrease and the tension of springs 64, 64 will increase. Consequently, the pressure with which the pads 61 engage the inner surface of the annular rim 52, and there- 50 fore the retarding friction or braking action exerted by the governor will gradually decrease as the power or torque exerted by the spring motor in driving shaft 18 decreases. The springs 64, 64 and 79, 79 and the other 55 parts of the governor are so designed and arranged that the braking action or retarding friction will vary directly in accordance with variations in the power or torque exerted by the motor in driving shaft 18 60 and, consequently, a uniform speed of the shaft 18 and therefore of the turntable 30, is obtained throughout the operation of the motor. It will be apparent that the action of the governor in maintaining the speed of 65 rotation of the shaft 18 and turntable 30

constant is not dependent in its action upon variations or fluctuations in such speed. With my improved governor it is possible to maintain a uniform speed of rotation of the turntable shaft substantially throughout 70 the unwinding of the spring motor 11. In case it is desired to adjust the uniform speed at which the phonograph is to be driven, it is merely necessary to turn the rod 69, as by means of a screw-driver, to thereby turn the 75 gear 66 on the collar 53 of shaft 18. This adjustment will effect a change in the normal tension of springs 64, 64 and 79, 79 and accordingly a change in the action of the governor which will result in a variation in 80 the uniform speed at which the shaft 18 and turntable 30 will be maintained when the phonograph is in operation.

A plate or bracket C is suitably secured as by means of screws to the upper side of 85 the central depressed portion 23 of the top plate 3, and pivotally mounted at P on this bracket is a brake lever B. One arm 82 of the lever B is provided with a brake pad 83 adapted to engage with the outer surface 90 of the annular rim 56 of disc 55, and a spring 85 secured at one end to the other arm 84 of the lever B and at its other end to a pin on the bracket C constantly tends to move the lever B about its pivot P to operative position. A detent 86 is pivotally mounted intermediate its ends on an extension of the bracket C at 87, and is provided at one end with a latch L adapted to coact 95 with the end of the arm 84 of the brake lever B to hold the latter in inoperative position as shown in Fig. 1. A coiled spring 88 surrounding the pivot 87 of detent 86 constantly tends to move the latter to operative 100 position. The end of the detent 86 opposite the end provided with the latch L, lies in the path of the segmental feeding rack 41, the arrangement being such that the feeding rack will engage the detent so as to release the brake lever B and effect the stopping of the phonograph when the reproducer has been fed inwardly to a predetermined point, preferably a point beyond that of the innermost groove of a record of maximum length. An angular start and stop lever S is also mounted on the pivot P between the brake lever B and the bracket C and comprises a short inner arm 89 and a long arm 90 extending outwardly through the opening or cut-out O and beyond the turntable 30 to a point adjacent the front of the cabinet 1. The arm 89 of lever S is provided at its opposite sides with a pair of upstanding lugs 92 and 93 embracing the arm 84 of the brake lever B and spaced apart sufficiently to permit a limited pivotal movement of lever S with respect to the brake lever B. At its angle the lever S is provided with an angular cam 94 adapted to coact 110 with the latch L of the detent 86. The ar- 115

angement of the parts is such that when the brake lever B is held in inoperative position by the detent 86 as shown in Fig. 1, and the lever S is moved about its pivot in a clockwise direction and relative to the brake lever B as is permitted by the spaced lugs 92 and 93, the cam 94 thereof coacts with the latch L to move the detent 86 to inoperative position and release the brake lever B and thereby effect the stopping of the phonograph; while when the brake lever B is in operative position as shown in Fig. 2, and the lever S is moved in an anti-clockwise direction about the pivot P, the lug 92 engages the brake lever B and moves the same toward inoperative position, and the cam 94 first coacts with the latch L to move the detent 86 to inoperative position, and then, as the end of arm 85 of lever B is moved past the latch L, the point of cam 94 will pass the latch L and permit the spring 88 to move the detent to operative position to thereby lock the brake lever B in inoperative position, as shown in Fig. 1. The extension of bracket C carrying the pivot 87 of detent 86, is provided with a pair of lugs for properly limiting pivotal movement of the detent in either direction. It will be apparent that with the construction just described, the turntable 30 may readily be removed from the shaft 18 when the phonograph is not in operation without releasing the brake mechanism and thereby effecting operation of the phonograph and the unwinding of the spring of motor 11.

While I have described and shown my improved governor in connection with a device driven by a spring motor, it is to be understood that the same is applicable for use with other types of motors, and I have found that it is especially adapted for use with electric motors in which the power or torque exerted during operation is subject to frequent and wide variations or fluctuations. It is also to be understood that my invention is subject to numerous other changes and modifications without any departure from the spirit of the invention or the scope of the appended claims.

Having now described my invention, what I claim as new and desire to protect by Letters Patent of the United States is as follows:

1. In combination, a rotatable member adapted to be driven by a motor, a governing device for controlling and regulating the speed of rotation of said member, and means responsive to variations in the power exerted by the motor in driving said member and acting on said governing device to vary the action of the latter in accordance with said variations to thereby maintain the speed of rotation of said member constant, substantially as described.

2. In combination, a driven member, a

motor connected to drive said member, a governing device exerting a braking action to control the speed of said member, and means responsive to variations in the power exerted by the motor in driving said member and acting on said device to vary the braking action exerted thereby in accordance with said variations, substantially as described.

3. In combination, a rotatable driven member, a motor connected to rotate said member, a governing device exerting a braking action to control the speed of rotation of said member, and means responsive to variations in the torque exerted by said motor in rotating said driven member and acting on said device to vary the braking action exerted thereby in accordance with said variations, substantially as described.

4. In combination, a driven member, a spring motor connected to drive said member, a governing device exerting a braking action to control the speed at which said member is driven, and means responsive to variations in the power exerted by the spring of said motor in driving said member and acting on said device to vary the braking action exerted thereby in accordance with said variations, substantially as described.

5. In combination, a rotatable driven member, a spring motor connected to rotate said member, a governing device exerting a braking action to control the speed of rotation of said member, and means responsive to variations in the power exerted by the spring of said motor in rotating said member and acting on said device to vary the braking action exerted thereby in accordance with said variations, substantially as described.

6. In combination, a rotatable driven member, a motor connected to rotate said member, a governing device exerting a frictional braking action to control and regulate the speed of rotation of said member, and means responsive to variations in the torque exerted by said motor in rotating said driven member and acting on said device to vary the frictional braking action exerted thereby in accordance with said variations, substantially as described.

7. In combination, a rotatable driven member, a motor connected to rotate said member, a governing device exerting a braking action to control the speed of rotation of said member, means responsive to variations in the torque exerted by said motor in rotating said member and acting on said device to vary the braking action exerted thereby in accordance with said variations, and means for adjusting said device to regulate the speed at which said member is rotated, substantially as described.

8. In combination, a rotatable driven member, a motor connected to rotate said

6
member, and a governing device for controlling and regulating the speed of rotation of said member, comprising means providing a fixed annular friction surface, a member loosely mounted for pivotal movement with respect to said rotatable member, resilient means connecting said members, a centrifugally operable element movably mounted on said loosely mounted member 10 and having a braking surface adapted to coact with said friction surface, and resilient means connecting said element and rotatable member opposing movement of said element under centrifugal action, substantially as described.

9. In combination a rotatable shaft, and a governing device for controlling and regulating the speed of rotation of said shaft, comprising means providing a fixed annular friction surface, a member loosely mounted on said shaft, resilient means connecting said member and shaft, a centrifugal weight or weights movably mounted on said member and each having a braking surface adapted to coact with said annular friction surface, and resilient means connecting said shaft and said weight or weights and opposing movement of the latter under centrifugal action, substantially as described.

10. In a phonograph, the combination of a rotatable turntable shaft, a motor connected to rotate said shaft, a stationary annular friction ring surrounding said shaft, a member loosely mounted on said shaft 35 and provided with one or more centrifugal weights movably mounted thereon and each having a braking surface adapted to coact with said friction ring, resilient means connecting said member and shaft, and resilient 40 means connecting said shaft to each of said weights and opposing movement of the latter toward said friction ring, substantially as described.

11. In combination, a rotatable shaft, and 45 a governing device for controlling and regulating the speed at which said shaft is rotated, comprising a stationary friction ring surrounding said shaft, a member loosely mounted on said shaft and provided 50 with one or more centrifugal weights movably mounted thereon and each having a braking surface adapted to coact with said ring, an element normally rotatable with said shaft but angularly adjustable with 55 respect thereto, resilient means connecting said element and member, and resilient means connecting said shaft and said weights opposing movement of the latter toward said ring under centrifugal action, 60 substantially as described.

12. In combination, a rotatable driven shaft, and a governor for controlling and regulating the speed of said shaft, comprising means having a fixed annular braking 65 surface surrounding said shaft, a centrif-

ugally operable member adapted to co-operate with said braking surface, mounted for rotation about the axis of said shaft and adapted for movement towards said braking surface under centrifugal action, 70 a connection comprising a resilient element between said shaft and said member to effect rotation of the latter about the axis of the shaft when the shaft is rotated, and resilient means opposing movement of said member toward said braking surface under centrifugal action, the arrangement being such that when the energy of said motor decreases in the operation thereof, the tension of said resilient element and said resilient means will automatically be respectively decreased and increased, substantially as described.

13. In combination, a rotatable driven shaft, a motor connected to rotate said shaft, and a governor for controlling and regulating the speed of said shaft, comprising means having a fixed annular braking surface surrounding said shaft, a centrifugally operable member adapted to co-operate with said braking surface, mounted for rotation about the axis of said shaft and adapted for movement towards said braking surface under centrifugal action, a connection comprising a resilient element between said shaft and said member to effect rotation of the latter about the axis of the shaft when the shaft is rotated, and resilient means opposing movement of said member toward said braking surface under centrifugal action, the arrangement being such that when the energy of said motor decreases in the operation thereof, the tension of said resilient element and said resilient means will automatically be respectively decreased and increased, and when the energy of the motor is increased during operation thereof, the tension of said resilient element and said resilient means will automatically be respectively increased and decreased, substantially as described.

14. In a phonograph, the combination of a rotatable record support, a shaft on which said support is mounted, a sound conveyer mounted for movement transversely of said support, feeding means for effecting said movement of the sound conveyer comprising an element carried by said conveyer, a member provided with a braking surface and carried by said shaft, a brake adapted to co-operate with said braking surface, and means for holding said brake in inoperative position, said element being arranged to release said holding means at a predetermined point in said movement of the sound conveyer, substantially as described.

15. In a phonograph, the combination of a rotatable turntable, a shaft on which said turntable is mounted, a sound conveyer mounted for movement transversely of said

turntable, feeding means for effecting such movement of the sound conveyer comprising an element carried by said conveyer, a governor for controlling the speed of rotation of said shaft, comprising a part rotatable with such shaft and having a braking surface, a brake adapted to co-operate with said braking surface, and means for holding said brake in inoperative position, 5 said element being arranged to release said holding means at a predetermined point in said movement of the sound conveyer, substantially as described.

16. In a phonograph, the combination of 15 a rotatable turntable, a shaft on which said turntable is mounted, a sound conveyer mounted for movement transversely of said turntable, feeding means for effecting such movement of the sound conveyer comprising 20 an element carried by said conveyer, a governor for controlling and regulating the speed of rotation of said shaft, comprising a member rotatable with such shaft and having an annular braking surface, a pivoted brake adapted to co-operate with said braking surface and biased to operative position, and a detent for holding said brake in inoperative position, said element being 25 arranged to release said detent at a predetermined point in said movement of the sound conveyer, substantially as described.

17. In a phonograph, the combination of

a cabinet, a support comprising a top plate normally occupying a substantially horizontal position in said cabinet, a turntable 35 shaft rotatably mounted on said support and extending vertically through said top plate, a motor mounted on said support below the top plate and operably connected with said shaft, a sound conveyer mounted 40 for movement transversely of said top plate, one end of said sound conveyer being disposed above said top plate, the sound conveyer extending rearwardly from said end above the top plate, then downwardly and 45 then forwardly below the top plate, and feeding means for effecting said movement of the sound conveyer comprising an element mounted on said support below the top plate and operatively connected with the 50 motor and an element carried by the sound conveyer and normally operatively engaging said first element, said support being pivotally mounted in said cabinet on a substantially horizontal axis and said feeding 55 elements being disengageable whereby the support may be swung upwardly in the cabinet about said axis so as to render accessible the parts carried thereby below said top plate, substantially as described. 60

This specification signed this 29th day of April, 1920.

WILLIAM E. GIBBS.
